UNITED STATES PATENT OFFICE.

JOHN H. BASTIAN, OF NEW BRITAIN, CONNECTICUT.

DESIGN FOR A HOLDBACK.

SPECIFICATION forming part of Design No. 23,474, dated July 17, 1894.

Application filed June 18, 1894. Serial No. 514,988. Term of patent 7 years.

To all whom it may concern:

Be it known that I, JOHN H. BASTIAN, a citizen of the United States, residing at New Britain, in the county of Hartford and State of Connecticut, have invented and produced 5 a new and original Design for a Holdback, of which the following is a specification, reference being had to the accompanying drawings, forming part thereof, in which—

10 Figure 1 is a perspective view of a holdback iron showing my design, and Fig. 2 is a reverse plan view of the same.

15 *a* designates the rear lug and *b* the front one, the former being in plan view in the form of two connected ovals and the latter in the form of an oval at its outer end with a

narrower straight edge portion *f* extending inwardly. Each of the lugs *a* *b* is provided with a screw hole *c* beveled on the under side.

d designates the body of the iron which extends down from the lug *a* quite abruptly, curving backwardly a little, and then slants gradually to the lug *b*, said body being of a rounded form in transverse section.

What I claim is—

20 The design for a holdback, substantially as shown and described.

25 JOHN H. BASTIAN.
